UNITED STATES PATENT OFFICE.

FRANK R. ASHLEY, OF EDGEWATER, COLORADO.

AUTOMATIC GATE-OPERATING MECHANISM.

Application filed January 4, 1922. Serial No. 526,933.

To all whom it may concern:

Be it known that I, FRANK R. ASHLEY, a citizen of the United States, and resident of Edgewater, in the county of Beaver and 5 State of Colorado, have invented an Improvement in Automatic Gate-Operating Mechanism, of which the following description, in connection with the accompanying drawings, is a specification, like letters on 10 the drawings representing like parts.

My present invention relates to gate operating mechanism, and more particularly to an automatic gate operating mechanism adapted to be utilized for the remote control 15 of gates, doors and the like.

At the present time, so far as the applicant is aware, there is no automatic gate operating mechanism on the market that is successful. Either the mechanism may be 20 operated only when the vehicle or load approaches the gate from one particular side, or the gate is opened so slowly or closed so quickly, as to interfere with the vehicle or load passing therethrough.

25 In my present invention I have overcome the defects of prior structures and have devised an improved and simplified gate operating mechanism that is positive in its operation, and that may be quickly and successfully operated by a vehicle or load approaching from either side. To this end I have arranged a trough running lengthwise of a roadway and extending transversely of a gate located at a suitable point in the roadway, and in this trough place levers operable 30 by the weight of a vehicle or load. Mechanism of this character is particularly desirable on large farms, ranches, industrial plants, stockyards, entrances to estates, and 35 the like.

The principal object of my invention is an improved means for mechanically operating a gate by the weight of a vehicle or load as such vehicle or load approaches the 40 gate.

Another object is an improved means for retaining a gate in open position until after a vehicle or load has passed therethrough.

Still another object is an improved means 45 for releasing the gate and moving it to its closed or normal position.

Other objects and novel features of the construction and arrangement of parts will appear as the description of the invention 50 progresses.

In the accompanying drawings illustrating preferred embodiments of my invention;

Fig. 1 is a central longitudinal section 60 through the trough containing the gate operating mechanism;

Fig. 2 is a plan view of Fig. 1, with the trough coverings removed;

Fig. 3 is an elevation of a gate extending transversely of a roadway, with the trough 65 illustrated in Figs. 1 and 2 shown in dotted lines;

Fig. 4 illustrates a modified form of connection between the runways or trough coverings and the gate operating weight;

Fig. 5 illustrates another modification of 70 connection between the runways or trough coverings and the gate operating weight;

Fig. 6 is a central longitudinal section 75 through the trough containing the gate operating mechanism, such mechanism being a modification of that illustrated in Fig. 1, and

Fig. 7 is another modification.

Referring to the drawings, 10 designates 80 a roadway at any suitable point of which is located a gate, comprising for example, posts 11, one at either side of the roadway 10, each post being provided with a plurality of lugs or eyes in which are rotatably mounted an upright shaft 12, while secured 85 to such shaft is a gate member 13. As illustrated these two gate members come together at a point midway of the two posts 11 to block the roadway 10 and may be rotated to clear such roadway for traffic.

Extending longitudinally of the roadway 90 on one side thereof and on either side of the gate members 13, is a trough 14. This trough is of any convenient length and inclines downwardly from its ends to a well 95 15 located directly under the gate members 13, when such members are in closed position. Also, at either end of the trough 13 is a depression 16 for a purpose to be hereinafter described. Rotatably mounted in suitable 100 bearings and extending transversely of the roadway 10 directly beneath the gate members 13 is a shaft 17, provided at each end with bevel gears 18 meshing with corresponding bevel gears 19 mounted on the lower ends of the shafts 12. Secured to said shaft 17 and normally extending downwardly therefrom is an arm 20 having adjustably secured thereto a weight 21. On either side of the shaft 17 and transversely 110

of the trough 14 is a shaft 22 having rotatably mounted thereon a bell crank lever 23, to the end of the upper arm of which is mounted a roller 24, while to the end of the 5 lower arm is attached one end of a wire or cord 25, the other end of this wire or cord 25 passing over a pulley 26 and being connected to the arm 20. This pulley 26 is rotatably mounted in the trough 14 on either 10 side of the well portion 15. A runway or cover element 27 engages the roller 24 and at its lower end is pivotally attached to the runway or cover element 28. A vehicle or load rolling over the runway 27 will depress 15 the same, rotating the bell crank lever 23 about its shaft 22 causing a pull on the wire or cord 25 to rotate the shaft 17 and, through the bevel gears 18 and 19, rotating the shafts 12 to open the gate members 13. 20 Mounted over the trough 14, is a runway or cover element 29 that is of a length sufficient to bridge the gap between the runway or cover elements 27 on either side of the shaft 17, thus making a continuous, 25 though broken, cover for the trough 14. Secured to the under side of the element 29 is a quadrant 30 provided with a notch 33 for engaging with a pawl 31 pivotally mounted on the rod 20. Rotation of the 30 shaft 17 in an anti-clockwise direction swings the arm 20 and lifts the weight 21, and the pawl 31, engaging in the notch 33, maintains said weight in the raised position until released, as hereinafter described. 35 Pivotedly mounted in suitable bearings in the roadway 10 and parallel to the shaft 17 and with one end extending into the trough 14 are two shafts 32 to one end of each of which is secured one end of a lever 34, the 40 free end of which extends upward through a slot in the middle of the roadway 10 and into engagement with a roller 35 carried by a vertically sliding member directly beneath the joining point of the two gate sections 13, 45 this member 36 being provided at its upper end with a catch 37 for retaining the gate sections 13 in closed position. To the other end of each shaft 32 is secured one end of a link 38, the other end of which is pivotally 50 attached to one end of a lever 39, pivotally mounted intermediate its ends on a shaft 40 mounted in bearings 41, and the free end of this lever 39 is provided with an upstanding portion 42 located beneath the hinged member 28. The weight of a vehicle on the 55 hinged member or runway 28 will depress the free end of the lever 39, raising the other end and depressing the latch 37 to free the gate members or sections 13. 60 On the shaft 17 is a pulley 43 and at either end of the trough 14 in the depression 16 is located a member 44. Mounted for vertical movement 44 is a trip plate 45 which rests on one arm of a pivoted bell crank lever 46 65 working in a vertical slot in the member 44.

To the other arm of said bell crank lever 46 is attached one end of a wire or cord 47 which works over the pulley 43 and has its other end attached to the pawl 31. Depression of the trip 42 causes a pull on the wire or cord 47 which in turn pulls the pawl 31 out of engagement with the notch 33 and the weight 21 causes a rotation of the shaft 17 to return the gate members 13 to their normal, or closed position. 75

My improved device may be operated by a vehicle approaching the gate from either side. Assuming that all parts of the device are assembled as above described, and as shown in Fig. 1, a vehicle approaching from the right hand side engages the trip 45 and then the pivoted runway elements 28 and 27, respectively. On the approach, nothing happens when the vehicle engages the trip plate 45, but the contact of such vehicle with the runway element 28 causes a depression of same and engagement therewith of trip 42. This causes a rotation of lever 39 on its shaft 40 and a lowering of the free end of lever 34, which in turn causes a depression of catch 37 and release of the gate members 13. The vehicle now reaches the runway portion 27 causing a depression of its free end and a rotation of the bell crank lever 23, which causes a pull on the wire or cord 25 to pull the arm 20 to rotate the shaft 17 and move the gate elements 13 to the open position, and simultaneously raise the weight 21, and the pawl 31 engaging the notch 33 maintains the weight in raised position until released. It is assumed that the vehicle contacts with the member 27 before leaving the member 28 and thereby starts the gate elements in motion before the catch 37 returns to its normal position. The distance between the gate and the pivoted end of the member 27 is sufficient to allow the gate members to swing fully open before the vehicle reaches the same and there is, therefore, no danger of the vehicle engaging with and stopping the operation of such gate members. 105 110

After the vehicle has passed through the gateway, the wheels of such vehicle engage with and depress the latch member 45, rotating the bell crank lever 46 and causing a pull on the wire or cord 47 to release the pawl 31 from the notch 33. This operation releases the weight 21 which, in returning to normal position, rotates the shaft 17 and moves the gate members 13 to normal or closed position, where they are caught and held by the latch 37. These operations may be performed by a vehicle approaching the gateway from either side. 115 120 125

In Fig. 4 I have shown an alternative means for operating the wire or cord 25, such means consisting essentially of a pivoted bell crank lever 50, to one arm of which is attached the end of the wire or cord 25 while the other arm is pivotally attached 130

to the lower end of a link 51, the upper end of such link being pivotally attached to the underside of the runway 27.

In Fig. 5 is still another form of operating means, in which a pulley 52, rotatably mounted on a shaft 53, has reeved thereover the wire or cord 25, and the end of this wire or cord is attached to the lower end of a link 54, pivotally mounted on the lower surface of the runway 27.

In Fig. 6 I have shown a modified form of my invention. In this form I provide runways on either side of the gate members 13, these runways comprising members 55 and 56 hinged together at 58, the member 55 being hinged at one end to a shaft 57 extending transversely of the trough 14, while the end of the member 56 remote from the point 58 engages with a roller 59 extending transversely of the trough 14. The weight 60 is supported by two wires or cords 61 and 62, both of which extend over a rotatable pulley 63 and under a rotatably mounted pulley 64, and one of these wires or cords, 25 as 61, passes over a rotatable pulley 65 and is attached to a depending member 66 secured to the bottom of the right hand member 55, while the wire or cord 62 extends around a rotatable pulley 68 and is attached to a depending member 69 secured to the bottom of the left hand member 55. To allow sufficient range of movement of the weight 60, I provide a well 70 at the bottom of the well 15. In this modification there is no necessity of locking devices to hold the weight 60 in raised position, as the weight of the vehicle on the hinged members 55 and 56 on one side of the gateway raises the weight to its uppermost position, 40 and the vehicle engages with the hinged members 55 and 56 on the other side of the gateway before moving off the first mentioned hinged members, thereby maintaining the weight 60 in the raised position until the vehicle has passed entirely through the gate.

In the modification illustrated in Fig. 7, the post 71 is erected at the middle portion of the trough 14, and extends upwardly to a point under the gate members 13. The top of the runway is indicated at either end of the trough 14 by the numeral 72, and hinged to said runway top is a member 55 pivotally connected to the member 56 by shaft 58, the roller 63 extending transversely of the trough 14 being mounted in the end of the member 56 adjacent the gate members 13. Secured in suitable bearings on the post 71 are rotatable sheaves 73 and 74, while mounted transversely of the trough 14, on each side of the post 71, is a sheave 75. Immediately beneath the center plate 76 is pivotally mounted a lever 77. Secured

at the lower end of the depending member 66 at the left hand member 55 is a cable 78 which passes over the sheave 75 and is secured to an eye 79 secured to a cable 80 that is attached to a point intermediate the ends of the lever 77. Secured at the lower end of the depending member 66 on the right hand member 55 is a cable 81 that passes over the right hand sheave 75, under the left hand sheave 75 and is attached to the eye 79. Secured to the lower end of the lever 77 is a cable 82 which passes under the sheave 73, over sheave 74, and has attached to its free end a weight 83. The operation of this modification is similar to the operation of the modification illustrated in Fig. 6.

While I have described and shown the preferred forms of my invention somewhat in detail, it is to be understood that I may vary the size, shape and arrangement of parts comprising my improved apparatus within wide limits without departing from the spirit of the invention.

Having thus described my invention what I claim as new, is:—

1. An improved automatic gate operating mechanism, comprising a roadway, a trough extending transversely of the gate, a shaft extending transversely of the trough and beneath the gate in its normal closed position, driving connections between the shaft and the gate for swinging the gate to open or closed position, an arm on said shaft extending into the trough and provided with a weight, a quadrant located in said trough, a pawl pivotally mounted on said arm and adapted to engage with said quadrant to hold the weight in raised position and the gate in open position, and means operable by the weight of a vehicle moving over the trough to operate the shaft.

2. An improved automatic gate operating mechanism, comprising a roadway, a trough extending transversely of the gate, a shaft extending transversely of the trough and beneath the gate in its normal closed position, driving connections between the shaft and the gate for swinging the gate to open or closed position, an arm on said shaft extending into the trough, and provided with a weight, a quadrant located in said trough, a pawl pivotally mounted on said arm and adapted to engage with said quadrant to hold the weight in raised position, and the gate in open position, and means operable by the weight of a vehicle to release the pawl from the quadrant to allow the weight to return the gate to closed position.

In testimony whereof, I have signed my name to this specification.

FRANK R. ASHLEY.
